UNITED STATES PATENT OFFICE

ADOLPH WILLSON, OF MINNEAPOLIS, MINNESOTA.

ADJUSTABLE FORM FOR ROUTING-MACHINES.

1,115,995.

Patented Nov. 3, 1914.

Application filed July 20, 1914. Serial No. 851,982.

To all whom it may concern:

Be it known that I, ADOLPH WILLSON, a citizen of the United States, residing at Minneapolis, in the county of Hennepin and State of Minnesota, have invented certain new and useful Improvements in Adjustable Forms for Routing-Machines; and I do hereby declare the following to be a full, clear, and exact description of the invention, such as will enable others skilled in the art to which it appertains to make and use the same.

My invention has for its object to provide a universally adjustable form or frame for holding work while it is subject to a routing tool; and to such ends, generally stated, the invention consists of the novel devices and combinations of devices hereinafter described and defined in the claims.

Hitherto, it has been the custom to build up a form for each article to be routed out, because the form must correspond to the size of the piece of work to be routed and must correspond to the shape of the panel or groove to be routed out.

My invention provides a form which, within certain limits, is universally adjustable to the various sizes and shapes of the different articles or pieces of work that are to be routed out.

The invention is illustrated in the accompanying drawings, wherein like characters indicate like parts throughout the several views.

Referring to the drawings, Figure 1 is a plan view with some parts broken away, showing the improved form; Fig. 2 is a section taken approximately on the line $x^2 x^2$ on Fig. 1 and showing also a routing tool in operative position on the form; and Fig. 3 is a transverse section taken approximately on the line $x^3 x^3$ on Fig. 1.

The form is made up chiefly of two longitudinally extended laterally spaced members, each of which comprises a base rail 1, and two laterally spaced metal strips 2 and 3. The said strips 2 and 3 are rigidly secured to interposed spacing blocks 4, but they are adjustable in respect to the base rails 1. As shown, this adjustment is accomplished by slotted brackets 5 secured to the strips 2 and adjustably secured to said base rails 1 by nut-equipped bolts or screws 6. The inner strips 2, as will hereinafter appear, serve as guide rails, and their ends project and are adjustably connected by

threaded rods 7 and coöperating clamping nuts 8.

Secured on the rails 2 are bearing lugs 9, through which work screw threaded stems 10 of vertically adjustable form, supporting rest blocks or feet 11, which, as shown, are of disk-like form.

The numeral 13 indicates spacing and guiding blocks which are adapted to be clamped between the rails 2.

The numeral 14 indicates a board or other piece of work which is formed with a routed out panel 14^a.

The numeral 15 indicates the bell-shaped body of an electric routing machine of well known construction, and which is provided with a routing tool 16 having a loose guide collar or roller 17 that is adapted to run in engagement with the rails 2 and inner ends 75 of the blocks 13.

As is evident, the width of the form may be adjusted by movements of the nuts 8 on the spacing rods 7, while the length of the work holding portion of the form may be varied by adjustments of the spacing blocks 13 between the rails 2. The projection of the guide rails 2 over the edges of the work 14 may be varied by adjustments of the brackets 5, in respect to the clamping bolts 6. 85 The combined spacing and guiding blocks 13 are simply blocks of wood which are cut according to the width of the panel that is to be routed out of the piece of work.

When the form is applied to the work, the base rails 1 are adjusted against the sides thereof, while the guide rails 2 and spacing blocks 13 are moved over the upper surface of the said work and the entire form is supported on the rest blocks 11 which rest directly on the upper face of the work. The work, itself, will be supported on the bed of the routing machine.

The vertically adjustable rest blocks 11 will rest upon the outer edge of the upper face of the work, and the depth of the cut of the routing tool may be varied by vertical adjustments of the said blocks 11. It will thus be seen that this form is adjustable, not only to the size of the exterior of a piece of work, but also, as to the depth of the cut and the outline of the panel to be routed out. Also, it is evident that this form may be very quickly adjusted to various sizes and shapes of work.

The wooden blocks 13 are adjustable but securely held to the guide rails 2, preferably

by long wood screws 18, which are passed through longitudinally spaced perforations 19 and screwed into the said blocks. The said perforations 19 are extended through 5 the rails 2 and 3 and through the intermediate spacing blocks 4, and are located at different points longitudinally of the rails, so that the spacing blocks 13 may be secured in any desired adjustment. When the 10 screws 18 are applied to the said rails and blocks, the rails are spaced apart by the blocks, so that, in some instances, the screw rods 7 might be dispensed with.

As is evident, the width of the piece of 15 work that will be held in the form is limited only by the length of the tie bolts 7, and it will, of course, be understood that tie bolts of any desired length may be employed.

By the use of this adjustable form, a great 20 saving of time, labor and material required, is accomplished.

What I claim is:

1. A form of the kind described comprising longitudinal guides, means for adjustably spacing said guides, and spacing and guiding blocks clamped between said longitudinal guides.

2. In an adjustable form of the kind described, the combination with laterally 30 spaced base rails, of guide rails adjustably secured on top of and projecting laterally from the inner edges of said base rails, and combined spacing and guiding blocks interposed between said guide rails.

3. A form of the kind described comprising longitudinal guides, means for adjustably spacing said guides, spacing and guiding blocks clamped between said longitudinal guides, and rest blocks engageable 40 with the work and adjustable to raise and lower said guide rails in respect to the work.

4. In an adjustable form of the kind described, the combination with laterally spaced base rails, of guide rails adjustably 45 secured on top of and projecting laterally from the inner edges of said base rails, combined spacing and guiding blocks interposed between said guide rails, bearing lugs on said guide rails, and rest blocks having 50 threaded stems adjustably engageable with said lugs.

5. In an adjustable form of the kind de-

scribed, the combination with laterally spaced base rails, of guide rails adjustably secured on top of and projecting laterally 55 from the inner edges of said base rails, combined spacing and guiding blocks interposed between said guide rails, and threaded spacing bolts connecting the ends of said guide rails for lateral adjustments. 60

6. In a form of the kind described, the combination with base rails, of guide rails provided with slotted brackets, bolts applied to said brackets and base rails adjustably securing said guide and base rails for 65 lateral adjustments, said guide rails having bearing lugs, rest blocks having end stems engageable with said lugs, nut-equipped threaded bolts adjustably connecting the ends of said guide rails in lateral adjustments, and combined spacing and guiding blocks clamped between said guide rails. 70

7. In an adjustable form of the kind described, the combination with laterally 75 spaced base rails, of guide rails adjustably secured on said base rails, spacing blocks interposed between said guide rails, and means directly and positively connecting said guide rails and spacing blocks.

8. In an adjustable form of the kind described, the combination with laterally spaced base rails, of guide rails adjustably secured on said base rails, spacing blocks interposed between said guide rails, and screws passed through perforations in said 85 guide rails and screwed into said spacing blocks.

9. In an adjustable form of the kind described, the combination with laterally spaced base rails, of guide rails adjustably 90 secured on said base rails, spacing blocks interposed between said guide rails, screws passed through perforations in said guide rails and screwed into said spacing blocks, and rest blocks adjustably secured to said 95 rails and adjustable to support said guide rails in different elevations above the work.

In testimony whereof I affix my signature in presence of two witnesses.

ADOLPH WILLSON.
